PISTON PUMP

James P. Johnson, Shaker Heights, Ohio

Application July 16, 1949, Serial No. 105,135

20 Claims. (Cl. 103—161)

1

The present invention relates generally as indicated to a piston pump and has for one of its primary objects the provision of a piston pump which is of simple fool-proof construction and of high mechanical and volumetric efficiency and which for a predetermined over-all size of unit has a considerably larger displacement than gear or vane type pumps of comparable size.

Other objects and advantages will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a cross-section view of one embodiment of this invention taken substantially along the line 1—1, Fig. 2;

Fig. 2 is a cross-section view taken substantially along the line 2—2, Fig. 1;

Fig. 3 is a perspective view of the intersecting and nested pistons employed in the Fig. 1 unit;

Fig. 4 is a cross-section view similar to Fig. 1 except illustrating a modification;

Fig. 5 is a perspective view of the intersecting pistons employed in the Fig. 4 unit;

Fig. 6 is a cross-section view taken substantially along the line 6—6, Fig. 7 of a still further modification;

Fig. 7 is a cross-section view taken substantially along the line 7—7, Fig. 6;

Fig. 8 is a cross-section view of a modification taken substantially along the line 8—8, Fig. 9;

Fig. 9 is a cross-section view taken substantially along the line 9—9, Fig. 8;

Fig. 10 is a cross-section view taken substantially along the line 10—10, Fig. 9;

Fig. 11 is a cross-section view of a still further modification taken substantially along the line 11—11, Fig. 12;

Fig. 12 is a cross-section view taken substantially along the line 12—12, Fig. 11;

Fig. 13 is an end elevation view as viewed from the right-hand end of Fig. 11; and

Fig. 14 is a cross-section view somewhat diagrammatic of a modification with multiple pistons so arranged as to balance the loads on the drive shaft.

2

In the embodiment of the invention illustrated in Figs. 1—3 there is provided a pump case comprising the case parts 1 and 2 bolted or otherwise secured together and defining therebetween a cylindrical chamber comprising parallel end walls 3 and 4 and a cylindrical bore 5, said bore being intersected at circumferentially spaced points by the ports 6 and 7 formed in the case part 2.

10 Non-rotatably fitted in such chamber is a liner sleeve or stator 8 preferably of bearing metal provided with slots 9 and 10 transversely through the wall thereof, said slots respectively communicating with the ports 6 and 7. The walls 3 and 15 4 of the case parts 1 and 2 may also be lined with plates 11 and 12 of bearing metal.

Having a free-running and sealed fit within said liner 8 and also with the plates 11 and 12 is a piston-carrying member or rotor 13 of hollow cylindrical form having an inner surface formed with two pairs of diametrically opposed and radially disposed grooves 14 spaced 90° apart and extending axially therethrough, said grooves providing piston chambers and being most readily and inexpensively formed as by broaching, for example. Said rotor 13 is further formed with a corresponding number of uniformly spaced openings 15 radially through the wall thereof and leading to the respective grooves 14 and adapted 20 to alternately communicate with the slots 9 and 10 in sleeve 8 during rotation of said rotor in said sleeve.

Diametrically across said rotor 13 and mounted in each pair of grooves or piston chambers 14 25 for reciprocation therein radially of said rotor is a piston 16 comprising, as best shown in Fig. 3, a head 17 at each end having a sliding seal with the side walls of the respective grooves 14 and a cut-away central portion 18 permitting intersection and nesting of the two pistons and independent reciprocation thereof along perpendicularly disposed paths. Each said piston 16 is further formed with a centrally disposed rectangular opening 19 axially therethrough, the 30 short sides of such opening being parallel to the radial path of reciprocation of the piston in its pair of grooves 14.

Extending through a boss 20 in the case part 1 is a drive shaft 21 having a square cross-section end portion 22 non-rotatably but transversely slidably extending into the openings 19 in said pistons 16 whereby rotation of said shaft will, through the pistons, effect rotation of the rotor 13 in sleeve 8.

55 Accordingly, the drive shaft 21 has a non-

rotatable and transversely slidable connection with each piston 16, such transverse sliding being along the long sides of each opening 19 or in other words along a path perpendicular to the radial path of reciprocation of the respective pistons.

As apparent, if said shaft 21 is coaxial with the rotor 13, driving of rotor 13 through pistons 16 will not effect any reciprocation of the pistons in piston chambers 14 radially of said rotor and accordingly the pump will then have zero displacement. On the other hand, it can be seen that if said shaft rotates about an axis eccentric to the central axis of rotor 13 and sleeve 8 as shown, not only will said rotor be rotated but said pistons 16 will be reciprocated radially of said rotor to draw fluid into the piston chambers 14 and openings 15 which are in communication with one of the slots 9 or 10 and to discharge fluid from the chambers which are in communication with the other of said ports 9 or 10. As illustrated, during rotation of drive shaft 21 and rotor 13 in a clockwise direction as viewed in Fig. 1, the chambers 14 will progressively expand in volume while in communication with the port 6 and slot 9 whereas the expanded chambers 14 will progressively decrease in volume while in communication with the port 7 and slot 10. Obviously, if said drive shaft 21 is rotated counter-clockwise, fluid will be drawn in through port 7 and discharged through port 6.

It will further be apparent to those skilled in the art that the unit illustrated in Figs. 1-3 may be operated as a fluid motor if desired, in which case fluid under pressure entering one of the ports 6 or 7 will cause rotation of the rotor 13 and shaft 21 and actuation of pistons 16 to discharge fluid from the other one of the ports 6 or 7. Moreover, because the rotation of sleeve 8 and rotor 13 is relative, said drive shaft 21 may be fixed against rotation and said sleeve 8 rotated about rotor 13.

In order to vary the displacement of the unit, the drive shaft 21 is journalled in a bearing 23 in the boss 20 of case part 1, said bearing and shaft being shiftable laterally of the axis of rotor 13 and sleeve 8 as by means of the laterally disposed screw 24 having threaded engagement with said bearing and locked in adjusted position as by a screw 25 which is threaded into boss 20 and frictionally clamps a collar portion 26 of screw 24 between one end of the adjusting screw 25 and a shoulder formed in boss 20. In the position of the parts as shown in Figs. 1 and 2 it is apparent that vertical adjustment of shaft 21 will correspondingly shift the vertically disposed piston 16, the horizontally disposed piston 16 then being in an intermediate position with the long sides of its rectangular opening 19 vertical for permitting vertical sliding of the square portion 22 of shaft 21 along such long sides.

In the unit illustrated in Figs. 1-3 the displacement per revolution of the rotor 13 will be equal to four times the product of the eccentricity "A" of the axes of shaft 21 and rotor 13, the width "B" and axial length "C" of each piston head 17. It is to be noted that because the pistons 16 are nested, the axial length of the unit will be a minimum.

In the form of the invention illustrated in Figs. 4 and 5, the rotor or cylindrical member 39 comprises an inner sleeve member 31 formed with cylindrical bores or piston chambers 32 diametrically therethrough and 90° apart and an outer sleeve member 33 non rotatably secured to

5 said inner sleeve member as by a screw 34. Said outer sleeve member is formed with openings 35 through the wall thereof spaced 90° apart so as to communicate with the bores or chambers 32 in the inner member 31.

In this form of the invention, one piston 36 is integrally formed at its opposite ends with coaxial heads 37 of circular cross-section having a close sliding fit in one pair of bores 32 and a web portion 38 connecting said heads together and having one side face passing through the axis of said heads, such web portion 38 being formed with a lateral opening 39 of rectangular cross-section centrally therethrough with the short sides parallel to the aforesaid axis of said heads.

The other piston 40 has circular cross-section and coaxial heads 41 and 42 at opposite ends thereof having a close sliding fit in the other pair of bores 32 in inner member 31 and a web portion 43 having one side face coinciding with the axis of the heads 41 and 42 whereby when the pistons 36 and 40 are assembled as in Fig. 5, the axes of the heads 37 and 41 and 42 will intersect with the web portions 38 and 43 in juxtaposed relation. Said web portion 43 also has a rectangular cross-section lateral opening 44 centrally therethrough with its short sides parallel to the axis of heads 41 and 42.

In order to facilitate assembly of the pistons 36 and 40 within inner sleeve member 31, head 42 is detachably connected to the end of the web portion 43 as by a screw 45 which extends through a hole in head 42 and is threaded into the web portion 43. Said web portion and head are preferably provided with complementary interfitting portions whereby to assure proper alignment of said head 42 with head 41.

As evident, piston 36 will first be inserted through one pair of diametrically opposed bores 32 to a position diametrically across member 31 and piston 40 with head 42 detached will similarly be slid into position in member 31 diametrically across the other pair of bores 32 and finally head 42 will be securely attached by means of screw 45. With the pistons 36 and 40 thus installed in intersecting relation in inner member 31, outer member 33 may then be slipped over said inner member and locked thereto by screw 34.

The above-described rotor assembly comprising inner member 31 with pistons 36 and 40 therein and outer member 33 therearound is then fitted into a liner sleeve or stator 46 of the same general construction as the liner sleeve 8 in Fig. 1.

Said sleeve 46 is formed with diametrically opposed transverse slots 47 and 48 through the wall thereof respectively communicating with the ports 43 and 53 in the case 51. Journalled in said case for rotation about an axis eccentric to the axis of sleeve 46 and rotor 39 is a drive shaft having a square cross-section portion 52 non-rotatably and transversely slidably extending through the respective rectangular openings 39 and 44 in the pistons 36 and 40.

Inasmuch as the operation of the unit illustrated in Figs. 4 and 5 is the same as Figs. 1-3, repetition thereof is not deemed necessary.

A further modification of the present invention as illustrated in Figs. 6 and 7 comprises case parts 55 and 56 secured together as by bolts 57 and defining therebetween a cylindrical chamber in which is disposed a rotary liner sleeve 58 transversely grooved on its inner surface as at 59 along diametrically opposed areas.

Having a running fit and seal within the eccentrically disposed bore in said liner sleeve 58 is a piston-carrying sleeve 60 formed with a plurality of uniformly spaced openings 61 radially through the wall thereof, there being preferably four such openings respectively leading into the piston chambers formed within said sleeve 60 as by axially extending grooves broached or milled in said sleeve. For purposes of illustration, the intersecting pistons 62 reciprocable in such chambers are the same as illustrated in Figs. 1-3. The openings 61 in sleeve 60 alternately communicate with the slots or grooves 59 in sleeve 58 and with ports 63 and 64 in case part 56 by way of an opening 65 adjacent one end of each groove 59.

Non-rotatably but transversely slidably extending through the rectangular openings 66 in said pistons is a square cross-section shaft 67 which is fixedly secured to case part 55 as by a lock nut 68 threaded onto one end of said shaft which extends through an opening 69 in case part 55. Said shaft 67 has a non-circular cross-section portion 70 thereon fitting within a complementary recess 71 also in said case part 55 whereby to hold the shaft 67 against rotation.

In this embodiment of the invention the driving of the unit to effect displacement of fluid thereinto and therefrom is effected by a drive shaft 72 journalled in a bearing 73 in case part 56 and having a toothed flange 74 integral therewith or fixed thereonto formed with teeth engaging in complementary notches formed in the end of sleeve member 58. The cylindrical wall 75 of the liner sleeve 58 with which the outer wall of sleeve 60 has a running fit is disposed eccentrically with respect to the axis of the drive shaft 72 and the square shaft 67 whereby rotation of said shaft 73 induces actuation of the sleeve 60 radially with respect to the pistons 62 on shaft 67.

Thus, when this unit is operated as a pump, rotation of drive shaft 72 will cause rotation of the sleeve member 58 and successively cause openings 61 to communicate with the slots or grooves 59. During such rotation, pistons 62 will each be reciprocated radially in sleeve member 60 thereby alternately drawing fluid into and discharging fluid from the piston chambers in said sleeve member, the displacement being in accordance with the eccentricity of cylindrical wall 75 relative to the axis of rotation of shaft 72. If desired, suitable means may be provided for adjusting the eccentricity.

Although the unit illustrated in Figs. 6 and 7 employs pistons 62 and a sleeve 60 similar to the pistons 16 and rotor sleeve 13 in Figs. 1-3, it will be understood that the pistons 36 and 40 in Fig. 5 together with the sleeves 31 and 33 might be similarly employed in this construction wherein a square shaft is non-rotatably and transversely slidably connected to pistons and is non-rotatably secured to the case of the unit and a liner sleeve is rotated to cause desired actuation of said pistons in a non-rotary piston-carrying member or sleeve.

Referring now to the unit illustrated in Figs. 8-10, the same comprises case parts 80 and 81 defining a cylindrical chamber 82 in which is disposed a liner sleeve 83 and washers or end plates 84, said sleeve and washers being of bearing metal and the former being formed with circumferentially extending slots 85 and 86 therethrough respectively communicating with the in-

take and discharge ports 87 and 88 in said case part 80.

Journalled in said casing as in the bearings 89 and 90 in the respective case parts 80 and 81 for rotation about an axis eccentric of the axis of liner sleeve 83 is a drive shaft 91 formed with a square cross-section portion 92 intermediate its ends and a collar portion 93 adapted to abut and slide against the end face of bearing 89. Said drive shaft 91 is preferably provided with a passage 94 therethrough communicating at one end with a passage 95 which leads to the intake or low pressure side of the unit whereby to preclude building up of pressure in the chamber 96 by leakage and consequent undesired axial thrust on said drive shaft.

The square portion 92 of said drive shaft has a non-rotatably but transversely slidable fit with the rectangular cross-section bores 97 and 98 respectively formed in the perpendicularly disposed pistons 99 and 100, such transverse sliding being along the long sides of the rectangular bores and at right angles to the axes of the respective pistons. Said pistons are of cylindrical form with the opposite ends of each having a close sliding fit within bores 101 and 102 diametrically through a piston-carrying member or sleeve 103, said member 103 having a close running fit within liner sleeve 83 and end plates 84.

As now apparent, the offsetting of the axes of bores 101 and 102 while axially lengthening the unit as a whole permits ready assembly of the pistons 99 and 100 in member 103 without requiring a detachable piston head as in the construction illustrated in Figs. 4 and 5. Furthermore, the provision of pistons 99 and 100 with relatively thick web portions has the effect of reducing the unit stresses on the walls of square portion 92 of drive shaft 91 and bores 97 and 98. Piston 99 is formed with a transverse slot 104, the bottom of which slidably engages the side of piston 100 to thus preclude turning of piston 99. Such slot is of width sufficient to allow reciprocation of said piston 99. Piston 100 is prevented from turning as by a flat wall 105 formed therein engaged with the collar 93 on drive shaft 91.

The operation of the unit illustrated in Figs. 8-10 is generally the same as the other units. It is to be noted that when the drive shaft is rotated clockwise as viewed in Fig. 8, the fluid under pressure in the discharge port 87 will have the effect of urging the pistons 99 and 100, the drive shaft 91 and the piston carrying member 103 toward the left whereby the latter will form a more effective seal with liner sleeve 83 whereby to assure pressure sealing of the intake side of the pump.

The unit illustrated in Figs. 11-13 comprises case parts 110 and 111 forming a cylindrical chamber in which is fixed a liner sleeve 112 formed with circumferentially extending slots 113 and 114 through the wall thereof respectively communicating with the ports 115 and 116 formed in case part 110. Having a running fit with said sleeve 112 is a piston carrying member 117 generally the same as member 103 in Figs. 8-10 except provided with an extension 118 projecting through a bearing 119 in the end of case part 110 by means of which extension said member 117 may be driven.

Insofar as the pistons 120 and 121 carried by said member 117 are the same as the pistons 99 and 100 in Figs. 8-10, description of the construction thereof has been omitted.

In this case, the square shaft 122 which non-

rotatably and transversely slidably fits in the rectangular openings through the respective pistons 120 and 121 is itself rotatable on an eccentric shaft 123, said shaft having one end fitted in a bearing 124 carried in member 117 and the other end extending through case part 111 with a radially extending arm 125 keyed thereto. Said arm is provided with a movable plunger 126 adapted to enter a desired one of the series of holes 127 formed in the case part 111.

From the foregoing, it can be seen that with the member 117 driven clockwise, for example, as viewed in Fig. 12, fluid will be drawn in through port 114 and discharged through port 113 by the actuation of the pistons 120 and 121. Now, if the arm 125 is shifted counter-clockwise, let us say 90°, the displacement of the unit will be zero because each piston will draw in and expel fluid while in communication with port 114 and will expel and draw back fluid while in communication with port 113. Of course, with the arm 125 at some intermediate position the displacement of the unit will be between zero and maximum.

On the other hand, if the arm 125 is turned 180° from the position shown, then the unit will be reversed without necessitating reversal of the direction of rotation of member 117, that is the port 114 will be the discharge port and port 113 the intake port. Similarly, by positioning of said arm between 90° and 180° there will be effected a displacement between zero and maximum. In any event, while the total piston movement does not ever change, there is effected a change in the displacement because of the movement of each piston in only one direction while communicating with one port for maximum displacement, the movement of each piston equal distances in opposite directions while communicating with one port for zero displacement, and the movement of each piston unequal distances in opposite directions while communicating with one port for displacement between zero and maximum.

It is to be understood that the displacement varying and reversing mechanism is merely typical and that other mechanisms may be substituted to provide for finer or closer adjustment than possible with the holes 127.

A still further modification of the present invention is the arranging of the pistons so as to balance the loads on the drive shaft, one such arrangement being shown somewhat schematically in Fig. 14 as comprising perpendicularly disposed pistons 130 and 131 similar to the pistons 99 and 100 in Fig. 9 carried in a member 132, said member 132 being rotatable in a liner sleeve 133 about an axis 134 eccentric of the axis 135 of the square drive shaft 136.

In order to balance the loads imposed on shaft 136 by discharge of fluid under pressure by piston 130 there is disposed thereadjacent and parallel thereto a piston 137 fitted on shaft 136 and carried in a member 138 which is also rotatable within liner sleeve 133 but about an axis 139 eccentric of drive shaft axis 135 but on the side thereof opposite the axis 134 of member 132. Similarly, the piston 131 is balanced by a piston 140 carried in a member 141 parallel thereto and thereadjacent, said member 141 being eccentric to member 132 whereby said pistons 131 and 140 move in opposite directions during the intake strokes and during the discharge strokes. Obviously said liner sleeve 133 and the casing therearound (not shown) will be provided with port-

5 so arranged that fluid will be simultaneously drawn into the unit by each pair of parallel pistons 130—137 and 131—140 and simultaneously discharged from the unit by each pair of said pistons.

Having thus described several embodiments of the present invention it will be apparent to those skilled in the art to variously modify the same and to incorporate therein any of the displacement adjusting devices or schemes disclosed in my copending applications Serial Nos. 56,439 now Patent No. 2,537,349 issued on January 9, 1951 and 56,490 now Patent No. 2,574,921 issued on November 13, 1951 which were filed on October 26, 1948.

Other modes of applying the principle of the invention may be employed, change being made as regards the details described, provided the features stated in any of the following claims, or the equivalent of such, be employed.

I therefore particularly point out and distinctly claim as my invention:

1. In a piston pump, the combination of a case formed with a cylindrical chamber and circumferentially spaced fluid intake and discharge passages leading to such chamber, a cylindrical member supported in said case for rotation about its central axis and formed with at least two radially disposed piston chambers 90° apart arranged to successively communicate with the passages in said case during rotation of said member, a piston in each such piston chamber extending radially inward of said cylindrical member, and a shaft member mounted in said case for rotation about an axis eccentric to the axis of said cylindrical member, said shaft member extending through one piston into the other and having a non-rotatable and transversely slidable connection with said pistons whereby to effect reciprocation of said pistons radially in such piston chambers responsive to rotation of said cylindrical and shaft members, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

2. In a piston pump, the combination of relatively rotatable inner and outer cylindrical members respectively formed with two pairs of diametrically opposed and radially disposed piston chambers and with fluid intake and discharge passages arranged to successively communicate with such chambers during relative rotation of said members, two pistons diametrically across said inner member each having its opposite ends reciprocable in one pair of such chambers, and another member extending through one piston into the other and having a non-rotatable and transversely slidable connection with an intermediate portion of said pistons and disposed eccentrically with respect to said inner and outer members, each of said pistons being formed with a lateral opening of non-circular cross section therethrough which opening provides parallel opposite sides perpendicular to the path of reciprocation of said piston, and said another member being of rectangular cross section having non-rotatable and transversely slidable engagement with the parallel opposite sides of the lateral opening in each piston.

3. In a piston pump, the combination of a case

formed with a cylindrical chamber and circumferentially spaced fluid intake and discharge passages leading to such chamber, a cylindrical member in such chamber and supported in said case for rotation about its central axis and formed with two pairs of diametrically opposed piston chambers arranged to successively communicate with the passages in said case during rotation of said member, two pistons diametrically across said member each having its opposite ends reciprocable in one pair of such chambers, and a shaft member journaled in said case for rotation about an axis eccentric to the axis of said cylindrical member, said shaft member extending through one piston into the other and having a non-rotatable and transversely slidable connection with an intermediate portion of said pistons whereby to effect reciprocation of said pistons radially in such piston chambers responsive to rotation of said cylindrical and shaft members, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

4. In a piston pump, the combination of relatively rotatable inner and outer cylindrical members respectively formed with four radially disposed piston chambers 90° apart and with fluid intake and discharge passages arranged to successively communicate with such chambers during relative rotation of said members, a pair of pistons diametrically across said inner member each having its opposite ends reciprocable in one pair of diametrically opposed piston chambers, and another member extending through one piston into the other and having a non-rotatable and transversely slidable connection with an intermediate portion of each of said pistons and disposed eccentrically with respect to said inner and outer members, each of said pistons being formed with a lateral opening of non-circular cross section therethrough which opening provides parallel opposite sides perpendicular to the path of reciprocation of said piston, and said another member being of rectangular cross section having non-rotatable and transversely slidable engagement with the parallel opposite sides of the lateral opening in each piston.

5. In a piston pump, the combination of a case formed with a cylindrical chamber and circumferentially spaced fluid intake and discharge passages leading to such chamber, a cylindrical member in such chamber and supported in said case for rotation about its central axis and formed with four radially disposed piston chambers spaced 90° apart arranged to successively communicate with the passages in said case during rotation of said member, a pair of pistons diametrically across said member each having its opposite ends reciprocable in one pair of diametrically opposed piston chambers, and a shaft member journaled in said case for rotation about an axis eccentric to the axis of said cylindrical member, said shaft member extending through one piston into the other and having a non-rotatable and transversely slidable connection with an intermediate portion of each of said pistons whereby to effect reciprocation of said pistons radially in such piston chambers responsive to rotation of said cylindrical and shaft members,

each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

- 10 6. In a piston pump, the combination of a case formed with a cylindrical chamber and circumferentially spaced fluid intake and discharge passages leading to such chamber, a cylindrical member in such chamber and supported in said case for rotation about its central axis and formed with four radially disposed piston chambers spaced 90° apart arranged to successively communicate with the passages in said case during rotation of said member, a pair of pistons diametrically across said member each having its opposite ends reciprocable in one pair of diametrically opposed piston chambers, a shaft member journaled in said case for rotation about an axis eccentric to the axis of said cylindrical member, said shaft member extending through one piston into the other and having a non-rotatable and transversely slidable connection with an intermediate portion of each of said pistons whereby to effect reciprocation of said pistons radially in such piston chambers responsive to rotation of said cylindrical and shaft members, and means for varying the displacement of said pistons, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

7. In a piston pump, the combination of a case formed with a cylindrical chamber and circumferentially spaced fluid intake and discharge passages leading to such chamber, a hollow cylindrical member having a close running fit in such chamber and supported in said case for rotation about its central axis, said member being formed with at least two radially disposed grooves 90° apart on its inner surface extending axially therethrough and with a passage opening into each such groove arranged to successively communicate with such intake and discharge passages in said case during rotation of said member therein, two pistons each reciprocable in one of such grooves radially of said member and extending radially inward of said member, and a drive member mounted in said case for rotation about an axis eccentric to the axis of said cylindrical member, said drive member extending within said cylindrical member and through one piston into the other and having a non-rotatable and transversely slidable connection with said pistons, each of said pistons being formed with a lateral opening of non-circular cross section therethrough which opening provides parallel opposite sides perpendicular to the path of reciprocation of said piston, and said drive member being of rectangular cross section having non-rotatable and transversely slidable engagement with the parallel opposite sides of the lateral opening in each piston.

8. In a piston pump, the combination of a case formed with a cylindrical chamber and circumferentially spaced fluid intake and discharge pas-

11

sages leading to such chamber, a hollow cylindrical member having a close running fit in such chamber and supported in said case for rotation about its central axis, said member being formed with two pairs of diametrically opposed radially disposed grooves on its inner surface extending axially therethrough and spaced 90° apart and with similarly spaced passages opening into the respective grooves arranged to successively communicate with such intake and discharge passages in said case during rotation of said member therein, a pair of intersecting pistons diametrically across said member each having its opposite ends reciprocable in one pair of diametrically opposed grooves radially of said member, and a drive member mounted in said case for rotation about an axis eccentric to the axis of said cylindrical member, said drive member extending within said cylindrical member and through one piston into the other and having a non-rotatable and transversely slidable connection with an intermediate portion of each of said pistons, each of said pistons being formed with a lateral opening of non-circular cross section therethrough which opening provides parallel opposite sides perpendicular to the path of reciprocation of said piston, and said drive member being of rectangular cross section having non-rotatable and transversely slidable engagement with the parallel opposite sides of the lateral opening in each piston.

9. In a piston pump, the combination of a case formed with a cylindrical chamber and circumferentially spaced fluid intake and discharge passages leading to such chamber, a hollow cylindrical member having a close running fit in such chamber and supported in said case for rotation about its central axis, said member being formed with at least two radially disposed bores 90° apart of circular cross-section providing two piston chambers arranged to successively communicate with such passages during rotation of said member, two pistons each reciprocable in one of such bores radially of said member and extending radially inward of said member, and a shaft member mounted in said case for rotation about an axis eccentric to the axis of said cylindrical member, said shaft member extending within said cylindrical member and through one piston into the other and having a non-rotatable and transversely slidable connection with said pistons, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

10. In a piston pump, the combination of a case formed with a cylindrical chamber and circumferentially spaced fluid intake and discharge passages leading to such chamber, a hollow cylindrical member having a close running fit in such chamber and supported in said case for rotation about its central axis, said member being formed with two pairs of diametrically opposed radially disposed bores spaced 90° apart and arranged to successively communicate with such passages during rotation of said member, a pair of pistons diametrically across said member each having its opposite ends reciprocable in one pair of diametrically opposed bores radially of said member, and a shaft member mounted in said case for

12

rotation about an axis eccentric to the axis of said cylindrical member, said shaft member extending within said cylindrical member and through one piston into the other and having a non-rotatable and transversely slidable connection with an intermediate portion of each of said pistons, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

11. In a piston pump, the combination of a case formed with a cylindrical chamber and circumferentially spaced fluid intake and discharge passages leading to such chamber, a hollow cylindrical member having a close running fit in such chamber and supported in said case for rotation about its central axis, said member being formed with two pairs of diametrically opposed radially disposed bores spaced 90° apart and arranged to successively communicate with such passages during rotation of said member, a pair of intersecting pistons diametrically across said member each having its opposite ends reciprocable in one pair of diametrically opposed bores radially of said member, and a shaft member mounted in said case for rotation about an axis eccentric to the axis of said cylindrical member, said shaft member extending within said cylindrical member and through one piston into the other and having a non-rotatable and transversely slidable connection with an intermediate portion of each of said pistons, each of said pistons comprising heads of circular cross-section closely fitting in such bores and an intermediate web connecting said heads together, one of said heads of one piston being detachably connected to the web thereof whereby to enable assembly of said pistons in intersecting relation within said cylindrical member, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

12. In a piston pump, the combination of a case formed with a cylindrical chamber and circumferentially spaced fluid intake and discharge passages leading to such chamber, a sleeve member rotatable in such chamber about an axis coinciding with the axis of such chamber and formed with passages successively communicating with the passages in said case during rotation of said member and with a cylindrical bore disposed eccentric to the axis of rotation of said member, a cylindrical member having a close running fit within such bore and formed with at least two radially disposed piston chambers 90° apart arranged to successively communicate with the passages in said sleeve member during rotation of the latter, two pistons each reciprocable in one of such piston chambers radially of said cylindrical member, and a member fixed in said case extending through one piston into the other and having a non-rotatable and transversely slidable connection with said pistons, each of said pistons being formed with a lateral opening of non-circular cross section therethrough which open-

13

ing provides parallel opposite sides perpendicular to the path of reciprocation of said piston, and said last-named member being of rectangular cross section having non-rotatable and transversely slidable engagement with the parallel opposite sides of the lateral opening in each piston.

13. In a piston pump, the combination of a case formed with a cylindrical chamber and circumferentially spaced fluid intake and discharge passages leading to such chamber, a sleeve member rotatable in such chamber about an axis coinciding with the axis of such chamber and formed with passages successively communicating with the passages in said case during rotation of said member and with a cylindrical bore disposed eccentric to the axis of rotation of said member, a cylindrical member having a close running fit within such bore and formed with two pairs of diametrically opposed piston chambers 90° apart arranged to successively communicate with the passages in said sleeve member during rotation of the latter, a pair of intersecting pistons diametrically across said cylindrical member each having its opposite ends reciprocable in one pair of diametrically opposed piston chambers radially of said cylindrical member, and a member fixed in said case extending through one piston into the other and having a non-rotatable and transversely slidable connection with an intermediate portion of each of said pistons, each of said pistons being formed with a lateral opening of non-circular cross section therethrough which opening provides parallel opposite sides perpendicular to the path of reciprocation of said piston, and said last-named member being of rectangular cross section having non-rotatable and transversely slidable engagement with the parallel opposite sides of the lateral opening in each piston.

14. In a piston pump, the combination of a case formed with a cylindrical chamber and circumferentially spaced fluid intake and discharge passages leading to such chamber, a hollow cylindrical member having a close running fit in such chamber and supported in said case for rotation about its central axis, said member being formed with two pairs of diametrically opposed radially disposed bores spaced 90° apart and arranged to successively communicate with such passages during rotation of said member, a pair of pistons diametrically across said member each having its opposite ends reciprocable in one pair of diametrically opposed bores radially of said member, and a shaft member mounted in said case for rotation about an axis eccentric to the axis of said cylindrical member, said shaft member extending within said cylindrical member and through one piston into the other and having a non-rotatable and transversely slidable connection with an intermediate portion of each of said pistons, said pistons and shaft member being formed with interengaging faces arranged to hold said pistons in predetermined rotative positions in such bores, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

15. In a piston pump, the combination of a case formed with a cylindrical chamber and circumferentially spaced fluid intake and discharge

14

passages leading to such chamber, a hollow cylindrical member having a close running fit in such chamber and supported in said case for rotation about its central axis, said member being formed with two pairs of diametrically opposed radially disposed bores spaced 90° apart and arranged to successively communicate with such passages during rotation of said member, a pair of pistons diametrically across said member each having its opposite ends reciprocable in one pair of diametrically opposed bores radially of said member, and a shaft member mounted in said case for rotation about an axis eccentric to the axis of said cylindrical member, said shaft member extending within said cylindrical member and through one piston into the other and having a non-rotatable and transversely slidable connection with an intermediate portion of each of said pistons, one piston having a cutaway side portion to embrace the other piston and to retain said one piston in a predetermined rotative position with respect to the bores in which the same is reciprocable, said other piston being similarly formed with a cutaway side portion, and said shaft member being provided with a collar portion engaging the cutaway portion of said other piston whereby to hold said other piston against turning in the bores in which said other piston is reciprocable, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

16. In a piston pump, the combination of a case formed with a cylindrical chamber and circumferentially spaced fluid intake and discharge passages leading to such chamber, a cylindrical member supported in said case for rotation about its central axis and formed with at least two radially disposed piston chambers 90° apart arranged to successively communicate with the passages in said case during rotation of said member, two pistons, one in each of such piston chambers extending radially inward of said cylindrical member, a shaft member mounted in said case for rotation about an axis eccentric to the axis of said cylindrical member, said shaft member extending through one piston into the other and having a non-rotatable and transversely slidable connection with said pistons whereby to effect reciprocation of said pistons radially in such piston chamber responsive to rotation of said cylindrical and shaft members, said shaft member including an inner portion provided with trunnions coaxial with said cylindrical member, and means for rotating and locking said inner portion at a selected rotary position whereby to vary the displacement of the pump as desired, each of said pistons being formed with a lateral opening of non-circular cross section therethrough which opening provides parallel opposite sides perpendicular to the path of reciprocation of said piston, and said shaft member being of rectangular cross section having non-rotatable and transversely slidable engagement with the parallel opposite sides of the lateral opening in each piston.

17. In a piston pump, the combination of an outer member providing a cylindrical chamber and fluid intake and discharge passages leading into such chamber, and a rotor assembly rotatable in such chamber about the central axis of

15

such chamber and provided with passage means successively communicating with such intake and discharge passages during rotation of said rotor assembly, said rotor assembly comprising a tubular member formed with perpendicularly disposed bores diametrically therethrough, the axes of such bores being offset axially of said tubular member, a pair of cylindrical pistons reciprocable in the respective bores radially of said tubular member, and a drive shaft eccentric with such tubular member having a non-rotatable, transversely slidable connection with said pistons whereby to rotate said tubular member and to reciprocate said pistons therewithin, said pistons each having cylindrical ends, and one of said pistons having a recess on one side embracing the side of the other piston whereby to hold said one piston against rotation in its bore and to permit insertion of said one piston into its bore, followed by insertion of the other piston into its bore.

18. The pump according to claim 17 further characterized in that said other piston and said drive shaft are formed with juxtaposed surfaces holding said other piston against rotation in its bore.

19. The pump according to claim 17 further characterized in that said drive shaft extends through said pistons and has both ends supported for rotation about such eccentrically disposed axis.

20. In a piston pump, the combination of coaxial, relatively rotatable inner and outer members, said inner member being formed with at

16

least two radially disposed piston chambers 90° apart, said outer member being formed with fluid intake and discharge passages arranged to successively communicate with such chambers during relative rotation of said members, a radial piston reciprocable in each such chamber and formed with a lateral opening of non-circular cross section therethrough which opening provides parallel opposite sides perpendicular to the path of reciprocation of said piston in such chamber, and a single shaft of rectangular cross section having non-rotatable and transversely slidably engagement with the parallel opposite sides of the lateral opening in each piston, said shaft being disposed eccentrically with respect to said inner and outer members.
